UNITED STATES PATENT OFFICE.

JOHN TALBOT, OF SACRAMENTO, CALIFORNIA.

CIGAR-PERFORATOR.

SPECIFICATION forming part of Letters Patent No. 268,960, dated December 12, 1882.

Application filed September 18, 1882. (No model.)

To all whom it may concern:

Be it known that I, JOHN TALBOT, of Sacramento, county of Sacramento, State of California, have invented an Improved Cigar-Perforator; and I hereby declare the following to be a full, clear, and exact description thereof.

My invention relates to a device for perforating the tips of cigars so as to provide a draft through the cigar without cutting off the end; and it consists of a pair of semi-conical jaws hinged together, so that they may be opened and closed by handles or otherwise. Within these jaws are a series of projecting pins, which, when the end of a cigar is inserted and the jaws closed, will perforate the cigar-tip transversely.

Referring to the accompanying drawings for a more complete explanation of my invention, Figure 1 is a view of my device in a portable form. Fig. 2 is a view showing it fitted to a stand for counter use.

A are two jaws, having handles B. The shanks cross each other and are pivoted like a pair of shears, so that the jaws may be separated or brought together by the action of the handles. These jaws are each made in the form of a hollow semi-cone, and have pins or perforators C fixed in them, so as to cross each other transversely at a sufficient distance apart when the jaws are closed to perforate the cigar-tips from opposite sides and in a sufficient number of places to give a free draft. This arrangement is superior to any perforation from one side alone, because it forms a greater number

of holes and at a number of different points, 35 which insures a more certain and free draft. When it is desired to employ it upon a counter or in a fixed position the handles behind the pivot may be omitted and the lower jaw be fixed within a suitable standard. 40

The upper jaw may have a loop or eye, d, at the top and be connected with a stem, e, which extends up through the top of the standard, having a knob at the top by which it may be depressed whenever desired. A spiral or 45 other spring, F, returns it when released.

The standard may have an opening at the side just in front of the perforating-jaws, into which the top of the cigar is thrust, and the knob depressed, thus perforating the tip, as 50 before described.

I am aware that perforating devices have been employed in which needles have been forced through the cigar-tip from one side, and I do not claim broadly such a construction; but 55

What I do claim as new, and desire to secure by Letters Patent, is—

A cigar-perforator consisting of the pivoted semi-conical jaws A, provided on their interior faces with pins c, in combination with operating handles, as set forth. 60

In witness whereof I hereunto set my hand.

JOHN TALBOT.
